UNITED STATES PATENT OFFICE.

HERMANN CHRISTIAN FISCHER, OF VIENNA, AUSTRIA-HUNGARY, AS-SIGNOR OF ONE-HALF TO JOHN CHRISTIAN KIRSCH, OF VIENNA, AUSTRIA-HUNGARY.

CHAIN-STITCH SEWING-MACHINE.

SPECIFICATION forming part of Letters Patent No. 793,127, dated June 27, 1905.

Application filed June 17, 1904. Serial No. 212,969.

To all whom it may concern:

Be it known that I, HERMANN CHRISTIAN FISCHER, a subject of the Emperor of Austria-Hungary, and a resident of 8 Grillparzerstrasse 1, Vienna, in the Empire of Austria-Hungary, have invented certain new and useful Improvements in Chain-Stitch Sewing-Machines, of which the following is a specification.

10 My invention relates to improvements in chain-stitch sewing-machines.

The principal objects of my invention are to make it possible to arrange a number of ring-shaped loopers or hooks together in 15 which in order to insure the loop being properly taken up the point of the looper or hook is formed nearer to its periphery; but in order to prevent the loop being taken up a second time by the point of the ring-shaped 20 looper or hook the latter is shaped in such a way that its ends overlap each other with an intervening space, so that the loop is only released after the point of the looper or hook has taken up the next loop. I attain these 25 objects, among others, by the mechanisms illustrated in the accompanying drawings, in which—

Figure 1 is a sectional elevation of the looper or hook. Fig. 2 is a sectional view 30 showing a number of loopers or hooks arranged close together. Figs. 3 and 4 are similar views to Fig. 1, showing the looper or hook in different positions during the formation of the stitch.

35 Similar figures refer to similar parts throughout the several views.

The looper or hook 1 is made in the form of a ring having two ends 3 4, which overlap each other for a suitable length, but having 40 a small intervening space 2 between them. The end 3 constitutes the point of the looper or hook, the object of which is, as described below, to seize or take up the loop formed in the thread and to thread it onto the ring, 45 while the outer end 4 is split and forked, (though the width of the ring is not altered,) so that the needle 5 can pass between the prongs or branches of the fork.

Inside the ring-shaped looper or hook and eccentric thereto the driving-spindle 6 is journaled, which when only one ring-shaped looper or hook is used is formed with a number of tappets 7—for instance, three, as shown in the drawings—which engage with projections or teeth 8, formed on the inside 55 of the ring-shaped looper or hook in such a way that the tappets only engage the projections or teeth for about the lower two-thirds part of their revolution and in the upper one-third part a space remains between the tappets and the projections, so as to permit the point 3 of the ring-shaped looper or hook to take up the loop and release it again easily. If, as shown in Fig. 2, a number of such ring-shaped loopers or hooks are arranged close 60 together, then the tappets 7 are shaped as longitudinal ribs, as shown, which actuate all the ring-shaped loopers or hooks uniformly. In this arrangement the ring-shaped loopers or hooks are preferably loosely fitted in one 65 cylindrical case 9, open at the top, which is attached at 10 to the bed-plate 11 of the machine, and the end 12 of which and spring-cover 13 are traversed by the driving-spindle 70 6. Between each of the ring-shaped loopers 75 or hooks and the next or when only one ring-shaped looper or hook is used on either side of it are fitted thin circular rings 14, fixed to the case 9, which in addition to keeping the rings separate from each other fulfil a further purpose mentioned below.

The operation of the ring-shaped looper or hook is as follows: In the position of the parts shown in Fig. 1 the loop 15, last formed, is taken up by the ring 1 and is held by the forked 85 end 4 and one end of the thin side rings 14 in such a position that the needle 5 can pass between the branches or prongs of the fork into this loop 15, and thus pass a new thread 17 through the material 16. The rings 14 are 90 arranged in close proximity to the prongs of the forked ends 4 and in this manner offer a certain resistance to the passage of the loop 15 over a certain portion of the rings and their prongs. The loop 15, however, is freed from 95 the ends of the rings 14 shortly before the

needle 5 passes into the loop 15. If now the ring-shaped looper or hook rotates farther in the direction of the arrow, then the point 3 of the looper or hook passes between the needle 5 and the rear thread of the loop 17, formed by the ascent of the needle, and holds this new loop fast in spite of continued rise of the needle. Only after the new loop 17 has been seized is the loop 15 released from the fork 4, 10 Fig. 3, by which means it is prevented from being seized a second time by the looper or hook point 3, and when the needle 5, Fig. 4, has risen the new loop 17 is drawn at 18 upon the gradually-widening part of the ring 1 onto 15 the fork 4, by which operation it receives its largest width. Loop 17 now takes the place of loop 15 upon the forked end 4 of the ring 1, and the method described is repeated. The fixed rings 14 are formed with two ends separated at the top, and the left end of same extends, Figs. 1, 3, and 4, beyond the point where the needle passes inside the loop 15, Fig. 1, so that it holds the latter fast partly directly and partly through the friction between the 25 inserted ring and the looper or hook. By this means the loop is prevented from being moved too much to the left by the pull of the thread, in which case the needle could not pass through the loop 15.

30 Having thus described the nature and objects of my invention, what I claim as new, and desire to secure by Letters Patent, is—

1. In a machine of the character described, circular loopers each of said loopers having 35 forked ends adapted to receive a loop and to permit the entering of a needle into and beyond said loop, a hook-shaped end extending below said forked ends and adapted to engage the thread on said needle below the loop held 40 by said forked ends and to form in conjunction with said ends, a passage-way adapted to permit of the casting off of the loop from said forked ends in a plane above the loop of the thread engaged by said hook-shaped end,
- 45 and means arranged between said circular loopers adapted to engage and to release the loop held by the forked ends prior to the entering of the needle into said loop.

2. In a machine of the character described,

circular loopers each of said loopers having 50 forked ends adapted to receive a loop and to permit the entering of a needle into and beyond said loop, a hook-shaped end extending below said forked ends and adapted to engage the thread on said needle below the loop held 55 by said forked ends and to form in conjunction with said ends a passage-way adapted to permit of the casting off of the loop from said forked ends in a plane above the loop of the thread engaged by said hook-shaped end 60 and fixed rings arranged between and adjacent to said rotating circular loopers having separate ends forming a space in advance of said needle, said rings adapted to engage and disengage the loop on said forked ends prior 65 to the entering of the needle into said loop.

3. In a machine of the character described, circular loopers, each of said loopers having forked ends adapted to receive a loop and to permit the entering of a needle into and beyond said loop, a hook-shaped end extending below said forked ends and adapted to engage the thread on said needle below the loop held by said forked ends and to form in conjunction with said ends a passage-way adapted to 70 permit of the casting off of the loop from said forked ends in a plane above the loop of the thread engaged by said hook-shaped end, and means arranged between said circular loopers adapted to engage and to release the 75 loop held by the forked ends prior to the entering of the needle into said loop, in combination with a driving-spindle having tappets traversing said loopers and said means, said spindle and tappets arranged eccentrically 80 with respect to the interior face of said circular loopers to permit of successive engagement and disengagement of each of said tappets with a complementary projection on the circular loopers in the rotation of the same. 85

In testimony whereof I have hereunto set my signature in the presence of two subscribing witnesses.

HERMANN CHRISTIAN FISCHER.
